AUTOMATIC PHOTOGRAPHIC SHUTTER

Nicholas V. Fedotoff, Lynbrook, N. Y.

Application December 2, 1937, Serial No. 177,757

4 Claims. (Cl. 95—60)

This invention relates to photographic shutters and particularly to such shutters in which the time of exposure is automatically controlled by the intensity of the light upon the object photographed.

The object of this invention is to provide a shutter capable of giving accurate exposures over a wide range of illumination intensities, and of giving extremely short exposures when required. 10 This application is a continuation-in-part of my copending application Serial No. 137,938, filed April 20, 1937.

This object is carried out in accordance with this invention by the provision of a pair of curtains one of which starts the exposure and the second of which terminates the exposure. A delay means responsive to the light intensity controls the time of closing of the shutter by the second curtain in such a manner that the inertia of moving parts is eliminated as a factor in the undesirable prolonging of exposures, thus making extremely short exposures possible.

For a better understanding of the invention, together with other and further objects thereof and advantages achieved thereby, reference may be had to the following description taken in connection with the accompanying drawing, and its scope will be pointed out in the appended claims.

In the accompanying drawing, the figure is a circuit diagram illustrating a shutter control system embodying the present invention.

The system here illustrated comprises a control circuit including the windings of electromagnets 10 and 11 having movable armatures, indicated at 10a and 11a, respectively, and connected in parallel in a series circuit including a suitable source of voltage, as, for example, a battery 12, and a manual control switch S.

For the purpose of preventing undue sparking and determining the period of operation of the magnets, a condenser 13 and resistor 13a are connected across the winding of the magnet 10, and a condenser 14 and resistor 14a are similarly connected across the winding of the magnet 11.

In order to control the period of operation of the magnet 11, there is provided time-control means preferably comprising a plurality of condensers 15—23, inclusive, adapted to be selectively connected in parallel with the condenser 14 by way of suitable leads 24 and 25, an adjustable member 26 having a contacting arm 27, and contacts 15a—23a individually connected to condensers 15—23, respectively. The member 26 may be pivotally movable, as indicated, to a position with its arm 27 adjacent one or more

contacts 15a—23a and also adjustable to cause its arm 27 to make and break contact with those contacts 15a—23a adjacent to which it has been moved.

For the purpose of effecting pivotal movement 5 of the member 26 to effect a time control in accordance with the value of illumination at a given source, indicated, for example, by the arrow A, there is provided a photoelectric cell P of a suitable type which may be connected, as shown, 10 in circuit with the winding of an electric magnet 28 having a movable armature 29. Where types of photoelectric cells are employed which require operating voltages and amplifiers, these may, of course, be employed in a conventional manner. 15 The armature 29 is suitably connected to the member 26 and, being movable when the magnet 28 is energized by the photocell to an extent determined by the value of illumination at the source A, serves to move the arm 27 relative to 20 the contacts 15a—23a, that is, to bring the arm to a position adjacent one or more of these contacts.

In order to complete the connection of one or more of the condensers 15—23 across the condenser 14, after the member has been adjusted by the armature 29 to a position corresponding to the value of illumination of the object A, an electric magnet 30 is provided, which has an adjustable armature 31 operably connected to 25 the member 26 for adjustment thereof to move the arm 27 into and out of contact with the contacts 15a—23a adjacent to which it has previously been moved. The winding of the magnet 30 is connected, in a series circuit including the battery 12 and a control switch S₂. The switch S₂ is operably connected to a second armature 32 of the magnet 11 to be actuated thereby.

In this embodiment of the invention, the system is used to effect related controls of two photoelectric shutters or curtains 33 and 34, of, for example, a camera, not shown. The curtains 33 and 34 are provided with suitable arm members 33a and 34a, respectively, which are operably connected to the armatures 10a and 11a of the 40 magnets 10 and 11, as shown, to be pivotally moved thereby. For the purpose of clarity of illustration, the curtains are illustrated as if spaced apart in the same plane. Actually, however, the curtains well overlap one another. 45

Openings 33b and 34b are found in the upper and lower portions, respectively, of the curtains 33 and 34, so that in the positions thereof which are indicated, and which will be assumed when the magnets 10 and 11 are deenergized, the 50 55

optical axis with reference to the object A, indicated at O, coincides with the center of the opening 33b, but light is prevented from passing through the composite curtain structure by the 5 upper solid portion of the curtain 33. Moreover, if both of the curtains are pivotally moved, by energization of their magnets, to upper positions, so that the center of the opening 33b coincides with the optical axis, the lower solid portion 10 of the curtain 33 will then prevent light from passing through the composite structure. Light will be permitted to pass through both curtains only when the curtain 33 is in its lower position and the curtain 34 is in its upper position, that 15 is, when the magnet 10 is deenergized and the magnet 11 energized.

In the operation of the system described, when the circuits of the magnets 10 and 11 are closed, current flows in their circuits increasing exponentially and actuating their armatures, and when their circuits are opened the current decays exponentially, releasing the armatures. The durations of the latter part of the cycles of operation are affected by the impedances connected 20 in circuit with the windings of the magnets, that is, the condensers and resistor in the embodiment shown. Since the greater the value of the capacitance in parallel with the magnet winding, the greater the period of the current decay, a 25 control is provided, by the provision of the adjustable capacitance means including the condensers 15a-23a, whereby a precise adjustment of the period of operation of the magnet 11 may be effected.

The general operation of the system may be described considering the curtains 33 and 34 to be applied to a camera to control its period of exposure. The photoelectric cell P may be disposed opposite an object to be photographed. The illumination of this object, or a desired part 40 thereof, according to the position of the cell, will then excite the cell and cause a flow of current through its circuit corresponding in value to the intensity of the energy radiated from, or 45 value of illumination at, the object. The magnet 23, therefore, will be actuated to adjust its armature 23 and, hence, the member 26 to a corresponding extent, thereby bringing the arm 27 adjacent a member of the contacts 15a-23a corresponding to the value of the illumination. 50 The switch S will then be closed completing the circuits of the windings of the magnets 10 and 11, which are thereupon energized with consequent movement of their armatures 10a and 11a to move both of the curtains 33 and 34 to their upper positions and the armature 32 to close the switch S₂, thereby completing the circuit of the magnet 30. The latter action by movement of armature 31 and member 26 effects contact between the arm 27 and as many of the contacts 15a-23a adjacent to which it has previously been moved by the photoelectric cell action.

When the operator is ready to expose the film, or take the picture, the switch S is simply released, thereby breaking the circuits of the magnets 10 and 11. The magnet 10 is constructed and arranged to have a relatively short, or substantially instantaneous, period of operation and will thereupon release its armature 11a and, 65 hence, bring the curtain 33 to its normal or lower position. Due to the time-control action of the circuit including the condenser 14 and such of the condensers 15a-23a as have been connected in parallel therewith, the period of action of the 70 magnet 11 is of a greater duration than that of 75

the magnet 10, or, more particularly, of a duration corresponding to the illumination at the object A. Hence, the return movements of the armature 11a and curtain 34 are correspondingly delayed with respect to those of the armature 10a and curtain 33, and the centers of both 5 openings 33b and 34b coincide with the optical axis O so that the light rays are permitted to pass entirely through the curtain structure into the camera. At the end of this period the armature 10 10 and curtain 34, of course, also assume their normal positions terminating the exposure.

It will be appreciated that a wide range of periods of exposure and exceedingly precise adjustments may be obtained by the system described, dependent upon the number and size of the condensers 15-23.

The advantage of the use of the two movable shutter curtains is that a very wide range of exposure periods is possible down to a very small 20 fraction of a second. The reason why extremely short exposures are possible is that the inertia of the shutter mechanism is eliminated as a factor in prolonging the exposure, which inertia would be a factor if only a single curtain were moved 25 to the opening position and then dropped back again. The reason the effect of inertia is eliminated is that the exposure does not start when curtain 34 is moved to the exposure axis, but instead, starts only when curtain 33 drops back 30 to the axis after curtain 34 is opened. Curtain 34 can be dropped back from the axis a much smaller fraction of a second after curtain 33 drops down to the axis than could curtain 34 35 itself be dropped back after its original opening.

For example, if both curtains be made of the same size and weight, as shown, and if there were no delay means at all delaying the return of the second curtain, both curtains would snap to normal at the same time, resulting in no exposure at all, even though each individual curtain mechanism possesses inertia. By reason of this ability of both curtains to start moving at the same time, it follows that the application of a small degree of delay will produce a correspondingly small exposure which can be made as small as desired down to zero exposure. If there were only one curtain it would be impossible to make the exposure zero or nearly zero.

While the particular system embodying the invention, which has been described, includes two actuating circuits for effecting two related control actions, it will, of course, be appreciated that other systems embodying the invention may be utilized which include only one actuating circuit 50 with time-control means therefor. Moreover, while a specific electric circuit arrangement including adjustable capacitance means has been described, it will be understood that various other equivalent arrangements will be readily apparent to those skilled in the art, where, for example, adjustable impedance means of other types are utilized in effecting the time control.

While there have been described what are at present considered to be the preferred embodiments of this invention, it will be obvious to those skilled in the art that various changes and modifications may be made therein without departing from the invention, and it is, therefore, aimed in the appended claims to cover all such changes 65 and modifications as fall within the true spirit and scope of the invention.

What is claimed is:

1. An automatic photographic shutter having an optical axis along which the exposure to an 75

object is made, comprising two movable curtains one of which is normally in an unobstructing position with reference to the optical axis and the other normally positioned to obstruct the axis so that the shutter is closed, relay means for operating the curtains, switch means for connecting the relays with an electrical source to move the first mentioned curtain to an obstructing position and the second mentioned to an unobstructing position, with reference to the axis, and then disconnecting said relays, means for returning the first curtain to its unobstructing position after said relays are disconnected to start the exposure, an electrical delay circuit set into operation at the start of the exposure, said delay circuit comprising electrical reactance connected with the relay which operates the second curtain for holding the latter relay energized for a period of time after said disconnection, reactance-varying means operated by a photoelectric cell which is subjected to the light on the object for varying said reactance according to the intensity of said light, and means for moving said second curtain to its normally obstructing position at the end of said time period to terminate the exposure.

2. An automatic photographic shutter having an optical axis along which the exposure to an object is made, comprising two movable curtains one of which is normally in an unobstructing position with reference to the optical axis and the second is normally positioned to obstruct the axis so that the shutter is closed, an operating device for setting the first curtain in an obstructing position and the second curtain in an unobstructing position, with reference to the axis, and then releasing said curtains, means for returning the first curtain to its unobstructing position upon said release to start the exposure, delay mechanism set into operation at the start of the exposure for holding the second curtain in the unobstructing position for a period of time after the return of said first curtain to maintain the exposure, said delay mechanism comprising a photoelectric cell subjected to the light on the

object, for determining the duration of said time in accordance with the intensity of said light, and means for moving said second curtain to its normal obstructing position at the end of said time period to terminate the exposure.

3. An automatic photographic shutter having an optical axis along which the exposure to an object is made, comprising two movable curtains each providing an aperture, said apertures being not both aligned with said optical axis in the normal unexposed position, an operating device for moving both of said curtains to align their apertures with the axis to start the exposure, delay mechanism operating during the exposure for holding the second curtain in the aligned position for a period of time after the alignment of the aperture of the first curtain, said delay mechanism comprising a photoelectric cell subjected to the light on the object, for determining the duration of said time in accordance with the intensity of said light, and means for moving said second curtain to its normal misaligned position at the end of said time period to terminate the exposure.

4. An automatic photographic shutter having an optical axis along which the exposure to an object is made, comprising two movable curtains, mechanism for moving the first of said curtains to an obstructing position and the second curtain to an unobstructing position with reference to the axis, an operating device for moving the first curtain to an unobstructing position to start the exposure, delay mechanism operating during the exposure for holding the second curtain in the unobstructing position for a period of time after the movement of the first curtain to the unobstructing position, said delay mechanism comprising a photoelectric cell subjected to the light on the object for determining the duration of said time in accordance with the intensity of said light, and mechanism for moving said second curtain to the obstructing position with reference to said axis at the end of said time period to terminate the exposure.
